Primary Examiner — Jonathan J Han*Assistant Examiner* — Molly K. Orzechowski(74) Attorney, Agent, or Firm — Luedeka Neely Group, P.C.(57) CLAIM

The ornamental design for a footwear, as shown and described.

DESCRIPTION

FIG. 1 is a perspective view of a footwear, showing my new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The broken lines in the drawings are included for the purpose of illustrating unclaimed features and form no part of the claimed design.

1 Claim, 4 Drawing Sheets(56)
